UNITED STATES PATENT OFFICE.

DANIEL N. TRULLINGER AND HERBERT A. TRULLINGER, OF AURORA, OREGON.

DEVICE FOR USE IN FORMING CONCRETE CONDUITS.

Application filed June 2, 1923. Serial No. 643,128.

To all whom it may concern:

Be it known that we, DANIEL N. TRULLINGER and HERBERT A. TRULLINGER, citizens of the United States, residing at Aurora, in the county of Clackamas and State of Oregon, have invented certain new and useful Improvements in Devices for Use in Forming Concrete Conduits, of which the following is a specification.

10 Our invention is a form for use in forming concrete conduits and has for its object the provision of a simple and inexpensive device which will be firmly supported while concrete or other cementitious material is being placed around it to form a pipe or conduit, and which may be readily shifted along the ditch as the work progresses to be used in the formation of a second section of pipe. The invention also has 15 for its object the provision of simple means whereby the form may be easily collapsed to permit its withdrawal from a formed pipe section, and also has for its object the provision of means whereby the end of the 20 formed section will be held against crumbling or collapsing while the device is being set in position for the formation of a succeeding section. Other incidental objects of the invention will appear in the course of 25 the following description.

In the drawing:

Figure 1 is a sectional elevation of our improved form showing it in position at the end of a ditch prior to the deposit of 30 material therein;

Fig. 2 is a similar view showing a part of a finished pipe section with the form in position for the production of a second pipe section;

40 Fig. 3 is an end elevation;

Fig. 4 is a detail section on the line 4—4 of Fig. 3, and

Fig. 5 is an enlarged detail section on the line 5—5 of Fig. 4.

45 In the drawing, the reference numeral 1 indicates a ditch or trench in which a concrete pipe or conduit is to be laid, and 2 indicates a part of a stand pipe or other structure which is set in the end of the ditch and with which the pipe or conduit is to be connected. This stand pipe is, of course, provided in one side with an opening whereby, when the conduit is formed, communication will be established between the conduit and the stand pipe, and in forming

the initial section of the conduit one end of the form is inserted in this opening, as clearly shown in Fig. 1. The form consists primarily of a sheet metal cylinder 3 formed of a single blank of the proper dimensions 50 with its longitudinal edges overlapping, as shown at 4. Within the cylinder adjacent the ends thereof, we arrange heads 5 consisting of semi-circular members 6 having their straight edge portions facing and normally abutting. The circular or arcuate edges of these sections may be covered with sheet metal, as indicated at 7, to resist wear, and one section is secured at any convenient point to the adjacent portion of the cylinder 55 3 by any convenient fastening device, as the screw 8. A contractile spring 9 is attached to the two sections and bridges the joint between the same, as clearly shown in Fig. 3, so that the sections are normally held together and the form will be in collapsed condition. Extending between the upper portions of the two sections of the heads is a rocking bar 10 having flattened or cam portions 11 adjacent its ends and equipped 60 with a handle 12 of any convenient form at its front end. The rocking bar is held against endwise movement by retainers 13 of any convenient or desired form fitted thereon against the outer faces of the respective heads and the flattened cam portions 11 of the bars fit between and against the straight edge portions of the sections, as will be readily understood. At the front end of the cylinder or form, we secure, as 65 90 by pins 17, to the under side thereof a shoe 14 whereby the said end of the form will be supported, and this shoe by resting upon the bottom of the ditch or trench 1 will support the cylinder in such position that 95 the grout or green cement may be permitted to reach the bottom of the trench under the form so that a complete pipe will be produced. We also provide a collar 15 which has an arcuate lower edge of the same 100 radius as the shoe 14, and this collar is slidably fitted about the cylinder 3. The opening through the collar is preferably slightly greater than the cross sectional area of the cylinder so that, when the cylinder is collapsed, the collar may be easily slid along the same and the upper portion of the collar may be of any desired outline, although it is preferably of the rectangular form shown most clearly in Fig. 3, where- 105 110

by it will conform to the cross section of the ditch or trench and will effectually restrain the concrete from passing beyond the collar and thereby being liable to collect in front of the form. On the front side of this collar or stop plate are mounted the vertically slideable anchor pins 18 which are adapted to enter the bottom of the ditch and thereby hold the collar while the cylinder is drawn forward.

The manner of using the device will, it is thought, be readily understood. Initially, the form is arranged with one end engaged in the opening in the stand pipe 2, as previously stated and as shown in Fig. 1, the collar or stop plate 15 being disposed adjacent the front end of the form and against the shoe 14. The green concrete or other plastic mixture is then poured into the ditch between the stand pipe and the collar or stop plate 15 and is tamped down in the usual manner of working concrete, the result being that a pipe, as shown at 16, will be produced around the form or mold. When the form is thus disposed, the rocking bar 10 is turned so that the edges of its flattened portions 11 will be presented to the straight or diametric edges of the head sections, and the said sections will be spread apart, as shown in Fig. 5, thereby firmly supporting the cylinder 3 in its expanded position. When the concrete has been partly set, the rocking bar is given a quarter turn so that the sides of the cams or flattened portions 11 will be presented to the straight edges of the head sections, whereupon the springs 9 will at once pull the said sections together, as shown in Fig. 3, and the cylinder 3 will collapse so that it will be loosened from the formed pipe section and may be then withdrawn to the position shown in Fig. 2. The cylinder will not be entirely withdrawn from the formed pipe section but its rear end will be left within the same so as to support it against collapse and while the cylinder is being thus shifted along the ditch, the collar or stop plate 15 will remain against the end of the formed section so that crumbling thereof will be very effectually prevented. By the time the cylinder has been properly positioned and again expanded, the end of the formed section will be sufficiently set to permit the collar to be moved away from the same, whereupon the anchor pins 18 are raised and the collar is shifted to the front end of the cylinder and anchored, as indicated by the dotted lines in Fig. 2, after which the operation of pouring and tamping the concrete may be repeated.

It will be readily noted that we have provided an exceedingly simple device whereby concrete conduits or pipes may be easily formed in the ditch in which they are to be placed and by the use of which a continuous

uninterrupted monolithic conduit will be produced. The rocking spreader bar will act directly upon the sections of the cylinder supporting heads which will respond quickly to the movement of the said bar or rod, and the edges of the split cylinder will overlap sufficiently to avoid the formation of an open joint even when the cylinder is fully expanded. The shoe 14 may be secured to the end of the cylinder by any convenient or preferred fastening devices, and these devices are preferably extended through the wall of the cylinder to present eyes 17 which may be engaged by any convenient form of tool whereby the mold may be drawn along the ditch to its successive working positions.

Having thus described the invention, what is claimed as new is:

1. A device for the purpose set forth comprising a longitudinally split cylinder having its side edges overlapping, divided heads fitted within the cylinder adjacent the ends thereof, means for holding the members of the heads normally together, and a spreader bar passing between the members of the heads and engaging the opposed edges of the same.

2. A device for the purpose set forth comprising a longitudinally split cylinder having its edges overlapping, head members disposed within the cylinder adjacent the ends of the same and having their diametric edges normally abutting, a spreader bar extending longitudinally of the cylinder and having cam portions at its ends fitting between the opposed edges of the head sections whereby to spread the said sections or permit them to abut, and a contractile spring attached to the sections of the heads and bridging the joint between the same.

3. A device for the purpose set forth comprising a split cylinder, means for collapsing or expanding said cylinder, a shoe secured to the under side of the cylinder at the front end thereof, and a collar slidably fitted upon the cylinder.

4. A device for the purpose set forth comprising a longitudinally split cylinder, means for expanding or contracting the cylinder, and a shoe secured to the under side of the cylinder at the front end thereof whereby to support the cylinder in spaced relation to the bottom of a ditch, the rear end of the cylinder being supported by a previously formed pipe section.

5. A device for the purpose set forth comprising a longitudinally split cylinder, means for expanding and collapsing said cylinder, means for supporting the front end of the cylinder, and a collar slidably mounted upon the cylinder and having its lower edge portion adapted to rest upon the bottom of the ditch in which the cylinder is placed.

6. A device for the purpose set forth comprising a longitudinally split cylinder, means for expanding and collapsing said cylinder, means for supporting the front end of the cylinder, a collar slidably mounted upon the cylinder and having its lower edge portion adapted to rest upon the bottom of the ditch in which the cylinder is placed, and means for anchoring the collar.
- 5 In testimony whereof we affix our signatures.
- of the cylinder, a collar slidably mounted upon the cylinder and having its lower edge portion adapted to rest upon the bottom of
